AMUSEMENT GAME BOARD

Bill Markham, Los Angeles, Calif., assignor to Lakeside Industries, Inc., Minneapolis, Minn., a corporation of Delaware

Filed Sept. 18, 1962, Ser. No. 71,750

Term of patent 14 years

(Cl. D34—5)

FIG. 1 is a front perspective view of an amusement game board embodying my new design; and

FIG. 2 is a top plan view thereof.

The sides not shown have substantially the same appearance as the side shown, the bottom being substantially plain.

I claim:

The ornamental design for an amusement game board, as shown and described.
